UNITED STATES PATENT OFFICE

RAYMOND P. LANSING, OF MONTCLAIR, NEW JERSEY, ASSIGNOR TO ECLIPSE MACHINE COMPANY, OF ELMIRA HEIGHTS, NEW YORK, A CORPORATION OF NEW YORK

ENGINE STARTER

Application filed January 18, 1928. Serial No. 247,727.

This invention relates to engine starting mechanism, and more particularly to mechanism of the inertia type for starting internal combustion engines.

5 It is an object of this invention to provide novel starting means adapted to be removably secured to the engine casing whereby energy stored in an inertia element may be employed for starting the engine.

10 Another object of the invention is to provide a novel inertia starter for engines which is so constructed that the energy of the inertia element or flywheel is transmitted to the engine crank shaft through a novel arrangement of two-step gearing.

15 Another object of this invention is to provide novel inertia starter mechanism adapted to be manually or automatically actuated.

A further object is to provide a novel 20 starter of the above type embodying means whereby a manually operable crank may be adjusted with respect to the body of the starter.

A further object is to provide a novel 25 starter comprising novel means for rigidly supporting the gearing therein.

Other objects include the provision of a 30 starter which is more efficient due to a reduction in the number of steps of gearing employed, one which is extremely light, and one embodying a very small number of parts. The above and other objects will appear more fully hereinafter in the detailed description of the invention.

35 Two embodiments of the invention are shown in the accompanying drawings, wherein like reference numerals refer to like parts throughout the several views, but it is to be expressly understood that the drawings are 40 for purposes of illustration only and are not designed as a definition of the limits of the invention, reference being had to the appended claims for this purpose.

45 In the drawings,— Fig. 1 is a perspective view of one embodiment of the present invention;

Fig. 2 is an axial section showing the apparatus of Fig. 1 installed on the rear end 50 of an engine housing, a portion only of the

latter being shown; and

Fig. 3 is an axial section illustrating one manner in which the apparatus of Figs. 1 and 2 may be combined with an electric motor.

Referring to Figs. 1 and 2, the starter mechanism comprises a housing constituted by a flanged inner portion 4 adapted to be bolted to the engine casing 5. Bolted to the outer face of flanged member 4 is a housing member 7, to the outer face of which is suitably secured, as by means of screws, a hand crank housing 8 provided with a plurality of openings 9 in the flanged portion thereof, whereby said housing 8 may be secured in any desired angular position to the housing member 7.

Rotatably mounted in the hand crank housing 8 is a shaft 10 which carries on the end thereof that projects outwardly from said housing, pins 11 adapted to be engaged by a hand crank (not shown). Preferably, pins 11 are constituted by the ends of a single pin extending through, and having a driving fit in, an opening formed in shaft 10.

Fixedly secured to the inner end of shaft 75 10 within the housing member 8 is a bevel gear 13 which meshes with a bevel gear 14 that is preferably formed integral with a sleeve 15. Supported in the housing member 7, closely adjacent bevel gear 14 and surrounding sleeve 15, is a ball bearing 16 for rotatably supporting the outer end of said sleeve. Bearing 16 is held against movement with respect to the housing member 7 by engagement with a shoulder formed in said member and an inwardly extending, flanged portion of housing member 8. A retaining nut 16a, threaded onto sleeve 15, holds bearing 16 against movement relative to said sleeve. The inner end of sleeve 15 is rigidly attached to a driving barrel 17 which is rotatably mounted, as by means of ball bearings 18 and 19, in the flanged housing member 4. The closed end of barrel 17 is provided with a flange 20 from which extend 80 three tubular sleeves 21, one of which is shown in section in Fig. 2. Each of these sleeves, which are spaced at intervals of 120° around the inner face of flange 20, is pressed into a counterbore in said flange, and is 85

90 95 100

formed integrally with a retaining ring 21a. Screws 21b pass through the sleeves and are threaded into flange 20. Ball bearings 22 are mounted on sleeves 21 and rotatably support three planetary gears 23, one of which is shown in section.

Rigidly secured to the face of the flanged housing member 4 is an annular gear 25 which surrounds and meshes with the planetary gears 23. Each of the latter gears is in mesh with a sun gear 26 which is rotatably mounted on the reduced portion of sleeve 15, and said sun gear is formed integrally with a spur gear 27 which is likewise rotatably mounted on sleeve 15 concentric therewith. Preferably, spacing washers 28 are interposed between spur gear 27 and a suitable shoulder formed on sleeve 15 to maintain said gear in proper position on the sleeve.

In engagement with spur gear 27 is a pinion 29 that is rigidly attached to the inner end of a shaft 30. The housing member 7 is provided with a hub 31 concentric with the longitudinal axis of shaft 30 and positioned in said hub are ball bearings 32 which rotatably support the hub of a flywheel 33 that is secured to shaft 30 for rotation therewith. To secure a more compact structure, the flywheel may be provided with an annular recess 34 into which hub 31 and ball bearings 32 project, so that the flywheel lies substantially in the vertical plane of hub 31. Preferably, a light metal cover 35 is secured as by means of screws to the outer face of housing member 7 to protect the flywheel.

When it is desired to rotate the flywheel in order to store energy therein for starting the internal combustion engine on which the starter is mounted, the operator actuates the hand crank and this motion is transmitted through shaft 10, bevel gears 13, 14, sleeve 15, driving barrel 17, planetary gears 23, sun gear 26, spur gear 27 and pinion 29 to the flywheel.

The energy of the rotating flywheel 33 is imparted to a starter jaw or driving member 36 that is adapted to mesh with, but is normally out of engagement with, a similar jaw 37 formed on the crank shaft 38, of the engine to be started, or an extension thereof.

It is desirable that yielding means be interposed between the flywheel and the jaw 36 in order that no injury may result to the gearing in the event of a backfire of the engine. Moreover, the inertia of the engine parts offers very high resistance at the instant of starting, and yielding means are desirable to facilitate the operation of the device in overcoming this inertia. For this purpose a multiple disk clutch is preferably interposed between starter jaw 36 and barrel 17, which latter, during the starting operation, is driven by the flywheel through the train of gearing described above. The yielding driving means constituted by the friction

clutch is not positioned in the gear train itself, but is interposed between said gear train and the engine, whereby each of the gears is protected against excessive forces such, for example, as are produced by a backfire of the engine.

In the form shown, the clutch mechanism comprises a plurality of plates 39 in interleaving and frictional engagement one with the other. One half of said plates are splined to the inner surface of the surrounding barrel 17, closely adjacent the closed end of the latter. Alternating with the plates that are splined to the barrel are the remaining half of the plates which have splined engagement at their inner peripheries with the outer surface of a nut 40, provided with a flanged portion 40a that bears against an annular bushing 41 which is L-shaped in cross section and which operatively engages the outer disk or plate 39. A spring spacer 42 bears against flange 40a and transmits to the latter the pressure of a plurality of coil springs 43 which have operative engagement at their outer ends with a clutch adjusting nut 54 threaded into the outer end of barrel 17. Preferably, springs 43 are maintained in spaced relation by means of suitable posts 55 which project inwardly from the inner face of said nut. Threaded within nut 40, and adapted for rotary, longitudinal movement relative thereto, is a shaft 56 provided with longitudinal splines at its outer end to receive the interiorly splined tubular portion 36a of starter jaw 36. Secured to the inner end of shaft 56 is a stop nut 56a for limiting movement of shaft 56 outwardly with respect to nut 40.

Means are provided for normally maintaining starter jaw 36 out of engagement with jaw 37, but said means are adapted to be actuated to move jaw 36 into engagement with jaw 37 on the engine crank shaft when the flywheel 33 has been brought to the desired speed of rotation. For this purpose a meshing rod 57 slidably extends through sleeve 15, shaft 56 and jaw 36, said shaft being provided, intermediate its ends, with a shoulder which normally engages the inner end of shaft 56. Surrounding the engine end of rod 57 is a spring 58 which bears at one end against the inner face of starter jaw 36 and at its opposite end against the threaded shaft 56. Preferably, the latter is provided with a recess into which a portion of spring 58 extends. The starter jaw is maintained on meshing rod 57 by means of a nut 59 threaded onto the outer end of said rod. The opposite end of meshing rod 57 terminates in the hand crank housing 8, and to said end is pivotally connected a lever arm 60 that is rigidly attached to a rock shaft 61. One end of shaft 61 projects exteriorly of housing 8 and carries a lever arm 62. A coil spring 63 surrounds rod 61, within the

housing 8, and one end of said spring is connected to lever arm 60 while the opposite end is anchored in the housing, the spring being so disposed as to act through rod 57 and nut 59 to maintain starter jaw 36 out of mesh with the jaw 37.

The operation of the device is as follows:— The operator rotates the hand crank and this motion is transmitted through bevel gears 13, 14, sleeve 15, barrel 17, planetary gears 23, sun gear 26, spur gear 27 and pinion 29 to the flywheel 33, whereby the latter is rotated. The rotation of barrel 17 acts through the clutch mechanism and shaft 56 to rotate the starter jaw 36 but said jaw is maintained out of driving engagement with the engine shaft by means of meshing rod 57 and spring 63. Since no load is on jaw 36, barrel 17, clutch plates 39, nut 40, shaft 56 and said jaw 36 rotate as a unit.

When the flywheel is brought to a sufficiently high speed of rotation, the operator exerts a pull to the right, as viewed in Fig. 2, on lever arm 62, whereby shaft 51 is rotated against the tension of spring 63, and meshing rod 57 is forced to the left. As pointed out above, shaft 56, nut 40 and jaw 36 are rotating in unison, but as rod 57 is moved to the left the shoulder on said rod forces threaded shaft 56 outwardly, relative to nut 40, and due to the threaded engagement of said shaft and nut, the longitudinal movement of the shaft is combined with a rotary movement relative to nut 40. A rotary movement relative to nut 40 is also imparted to jaw 36 due to the splined engagement of said jaw with shaft 56. Jaw 36, spring 58 and shaft 56 move outwardly as a unit until said jaw engages jaw 37, whereupon spring 58 yields to permit endwise movement of jaw 36 relative to screw shaft 56. Complete meshing of the jaws is thus insured and a jam on the corners of the teeth of said jaws is prevented.

When the shoulder on rod 57 has forced threaded shaft 56 outwardly to extreme position, i. e., when nut 56a has been moved into engagement with the threads of nut 40, shaft 56, starter jaw 36, and nut 40 rotate as a unit and the full energy of the flywheel 33 is now exerted on engine shaft 38 to rotate the same and start the engine.

The inertia of the movable parts of the engine, which parts are stationary at the instant jaw 36 is engaged with jaw 37, is so great, and the energy of the flywheel is so enormous in amount, that damage would frequently result to the light elements of the starter mechanism if no slippage were permitted between the flywheel and engine shaft, at the instant jaws 36 and 37 are engaged. Accordingly, the clutch is so adjusted, by adjustment of nut 54 and hence the tension of springs 43, as to permit some slippage between plates 39 at the instant the starter jaw 36 is engaged with jaw 37 on the engine crank

shaft, whereby relative rotary movement results between jaw 36 and barrel 17. As the speed of the engine crank shaft is brought up to the speed of jaw 36, the slippage between plates 39 decreases until finally the parts are rotated as through rigid or non-slipping connections. The use of a slippage connection, such as the multiple disk clutch, permits lighter parts to be used in the construction of the apparatus and this is of great importance when the apparatus is used for starting aeroplane engines.

After the engine starts under its own power the speed of rotation of jaw 37 becomes greater than the speed of jaw 36. The inclined faces of the teeth of the jaws now force jaw 36 away from the engine crank shaft in the event that rod 57 is being held in meshing position. When the operator releases lever arm 62, the tendency of jaw 37 to drive jaw 36 coacts with the threads of nut 40 and shaft 56 to completely demesh jaw 36 and return the shaft 56 to normal position. This action is facilitated by the return of rod 57 to normal position under the action of spring 63.

In view of the above, it will be apparent that no damage will result in the event that the operator does not release rod 57 as soon as the engine starts under its own power, since the splined connection between shaft 56 and jaw 36 permits the latter to be moved away from jaw 37 irrespective of a similar movement on the part of said shaft.

The starter mechanism shown in Figs. 1 and 2 is adapted to be energized by power means if desired. As shown more clearly in Fig. 3, an electric motor 64 is rigidly attached, as by means of screws, to the outer face of housing portion 7 above the crank shaft housing member 8, the flywheel cover 35 being removed prior to securing motor 64 in place.

Means are provided for automatically connecting and disconnecting the motor and flywheel whereby the latter may be rotated at high speed. For this purpose shaft 65 of the motor is provided with a threaded portion 66 on which is threaded for rotary and longitudinal movement, a clutch member 67 adapted to engage a clutch element 68 rigidly attached in any suitable manner to the outer face of flywheel 33. The outer end of motor shaft 65 is journalled in the adjacent end of tubular shaft 30, a bushing 69 preferably being interposed between these parts.

When motor 64 is energized the inertia of clutch member 67 coacts with threaded portion 66 of the motor shaft to move said clutch member longitudinally of the shaft into mesh with clutch member 68, whereupon the energy of the motor is effective to rotate flywheel 33. After the flywheel has been brought to the proper speed of rotation, the circuit to motor 64 may be opened, and the tendency of said

flywheel to drive clutch member 67 will result in the latter being returned to its normal position out of engagement with the clutch member 68. When motor 64 is employed the manual means for rotating flywheel 33 may still be employed, if desired, either selectively or cooperatively.

Due to the many types of aeroplane structures employed, it is frequently desirable to vary the angular position of shaft 10 relative to the starter housing, in order to facilitate the engagement of the hand crank with said shaft. The structure of the present invention is such that the desired adjustment of shaft 10 may be readily made even when motor 64 is employed. Rod 57 is also mounted in such a manner as not to interfere with this adjustment.

There is thus provided novel starting means adapted to be removably secured to the rear end of an engine housing. Less energy is required on the part of the operator in rotating the flywheel through the two-step gearing than would be required if a larger number of steps were used, and the transfer of energy from the flywheel to the starter jaw is more efficiently performed. The use of two-step gearing simplifies the construction and materially reduces the weight and size of the apparatus, which is of extreme importance in aeroplane use. The mechanism may be so constructed as to provide for either power or manual rotation of the flywheel.

35 Bevel gear 14 is securely mounted for rotation within the starter housing by means of ball bearings 16 and since said gear is formed integral with sleeve 15, it is held in alignment by barrel 17 and ball bearings 18, 19.

40 Various changes may be made in the details of construction and the arrangement of parts without departing from the invention defined in the following claims.

What is claimed is:—

45 1. In apparatus of the class described, a driven member, a driving member therefor, means including a yielding driving connection for operatively connecting said driving member and the driven member, a flywheel, means for rotating the flywheel, the axes of rotation of said driven member and flywheel being laterally spaced and substantially parallel, and a two-step gear train directly connected to said driving member and flywheel for transferring energy stored in the flywheel to said driving member.

50 2. In apparatus of the class described, an engine engaging driven member, means for transmitting rotation to said driven member including a rotatably mounted driving member operatively connected thereto, a flywheel, means for storing energy in said flywheel, the axes of rotation of said driven member and flywheel being laterally spaced and sub-

stantially parallel, and a two-step reduction gearing constituting the sole connection between said flywheel and driving member.

55 3. In apparatus of the class described, a flywheel, a pinion rigidly secured to the flywheel for rotation therewith, a plurality of planetary gears, a starter jaw, means including a yielding driving connection for operatively connecting said starter jaw and said planetary gears, a member comprising an integrally formed pinion and gear that constitutes the sole driving connection between the first named pinion and said planetary gears, and means for storing energy in said flywheel.

60 4. In combination with an engine to be started, said engine having a member to be driven, a starter element adapted to engage the engine member to be driven, a flywheel for actuating said starter element, a pinion secured to said flywheel for rotation therewith, means for transmitting rotation to said starter element including a driving barrel operatively connected to said element, planetary gears carried by said barrel, and means for operatively connecting said barrel and flywheel including an integrally formed pinion and gear operatively connected to said barrel, said gear meshing with and having direct driving engagement with said first named pinion, and said integrally formed pinion having direct driving engagement with said planetary gears.

65 5. In starting apparatus for internal combustion engines, a driven member, a flywheel, the longitudinal axes for said flywheel and driven members being parallel and laterally spaced, a pinion rigidly connected to, and actuated by, said flywheel, a gear meshing with and actuated by said pinion, a pinion concentric with said gear and rigidly connected thereto, planetary gearing meshing with and driven by said last named pinion, clutch means constituting a yielding driving connection interposed between said planetary gearing and said driven member, and manually operable means for storing energy in said flywheel.

70 6. In apparatus of the class described, a driven member, an inertia driving member, the longitudinal axes of the driving and driven members being parallel and laterally spaced, means including planetary gears for transmitting movement from the driving member to the driven member, manually operable means for storing energy in said driving member including a shaft, and means rotatably mounting said shaft, said last named means being adjustable whereby the angular position of said rotatable shaft, relative to said driving member, may be varied.

75 7. In apparatus of the class described, a member adapted to be driven, an inertia element for driving said member, two-step gearing means including planetary gears for im-

parting the energy of the inertia element to said driven member, and manually operable means for storing energy in said driving member, said manually operable member being angularly adjustable about an axis concentric with the axis of said driven member.

8. In apparatus of the class described, a housing, a flywheel rotatably mounted in said housing, means including an integrally formed gear and pinion adapted to rotate and adapted to be rotated by said flywheel, a bevel gear for rotating said first named gear, a bearing carried by said housing and adapted to rotatably support said bevel gear, and manually operable means for rotating said bevel gear, said manually operable means being angularly adjustable about the axis of rotation of said bevel gear.

9. In apparatus of the class described, a driven member adapted to engage the engine to be started, an inertia driving member for said driven member, two-step gearing including planetary gears for transmitting the rotation of the inertia member to said driven member, manually operable means for rotating said inertia member, the latter having its axis of rotation laterally spaced from the axis of rotation of said driven member, and electrical means for rotating said inertia member, said electrical means and said manually operable means being adapted for selective operation.

10. In apparatus of the class described, a driven member, an inertia driving member for the driven member, means including two-step gearing for transmitting the rotation of the inertia member to the driven member, electrical means for rotating said inertia member, manually operable means for rotating said inertia member, said electrical and manually operable means being adapted for selective and conjoint operation, and adjustable means for mounting the manually operable means whereby said manually operable means may be angularly adjusted about the axis of rotation of said driven member.

11. In apparatus of the class described, a driven member, an inertia driving member therefor, means including a yielding connection for transmitting the energy of the inertia member to said driven member, the axes of the driven and driving member being laterally spaced and substantially parallel, manual means for rotating said inertia member, and power means for rotating said inertia member, said power and manual means being selectively operable.

12. In apparatus of the class described, a housing, a flywheel rotatably mounted therein, a member adapted to be driven by said flywheel, means for transmitting rotation of the flywheel to said driven member, manually operable means including a gear for rotating said flywheel, a bearing for said gear, said bearing being removably mounted in

said housing, and a housing member for said manually operable means, said housing member constituting a retainer for said bearing.

13. An engine starter comprising a driven member adapted to be moved into engagement with a member of an engine to be started, a flywheel for rotating the driven member, the axes of rotation of said driven member and flywheel being laterally spaced and substantially parallel, means for imparting energy stored in said flywheel to said driven member, means concentric with the driven member for moving the latter into engagement with the engine member, and means for storing energy in the flywheel.

14. An engine starter comprising a driven member adapted to be moved into engagement with a member of an engine to be started, a flywheel for rotating the driven member, motion transmitting means operatively connected to said driven member and flywheel, means concentrically disposed with respect to the driven member for moving the latter into engagement with said engine member, manual means for rotating the flywheel, and a housing member for said manual means, said housing member and flywheel being laterally spaced with respect to a common plane disposed at right angles to said concentric means.

In testimony whereof I have signed this specification.

RAYMOND P. LANSING.
